UNITED STATES PATENT OFFICE

WILLIAM E. NICKERSON, OF CAMBRIDGE, MASSACHUSETTS, ASSIGNOR
TO GILLETTE SAFETY RAZOR COMPANY, OF BOSTON, MASSACHU-
SETTS, A CORPORATION OF MAINE.

METHOD OF HARDENING.

No. 812,442.

Specification of Letters Patent.

Patented Feb. 13, 1906.

Application filed September 26, 1903. Serial No. 174,739.

To all whom it may concern:

Be it known that I, WILLIAM E. NICKERSON, a citizen of the United States, and a resident of Cambridge, in the county of Middlesex and State of Massachusetts, have invented 5 a new and useful Method of Hardening, of which the following is a specification.

My invention relates to the art of hardening steel, and is intended to provide a simple 10 and practical method of hardening simultaneously and quickly a large number of thin strips or sheets of limited area.

My method has a special applicability to the hardening before sharpening of the thin 15 flat steel blades employed in the safety-razor shown and described in United States Letters Patent No. 775,134, granted on the 15th day of November, 1904, on the application of King C. Gillette and will be so described here- 20 in; but my invention is not limited to such use.

In hardening steel sheets which are as thin as are the blades above referred to it is important to protect the surfaces of the sheets 25 from contact with air while being heated, and especially from contact with the water of the chilling-bath when plunged therein while hot, in order to prevent the oxidation of the sheets which would result from such contacts 30 and would be likely to penetrate the sheets to such an extent as to greatly injure them or render them useless. It has been proposed to protect these blades from such contact by piling them in a compact stack and heating 35 them collectively and subsequently hardening them simultaneously by plunging them in a cold bath; but this process has been found to be impracticable, however, for the reason that the cold liquid which is applied 40 to the stack comes in contact with the surface of the stack only, or, in other words, with the edges only of the blades, with the result that each blade has its edges or rim set while the inside portion is still very hot, and thus 45 the hardened rim becomes slack and is caused to crinkle or become wavy when the blade is finally cooled to a uniform temperature throughout, thus destroying the straightness of the edges of the blade beyond restoration 50 and leaving the center unhardened.

According to my invention I pile a number of the blades in a stack; but instead of placing them all directly in contact one with an-

other I interleave between each few blades, and preferably between adjacent blades 55 throughout the stack, a sheet of some metal, such as copper or silver, which is a much better conductor of heat than is steel and has a melting-point high enough to resist the temperature to which the steel blades are heated 60 for hardening, copper being preferred. These sheets are preferably of such size that they will project slightly beyond the edges of the adjacent blades all the way around. This 65 stack of blades with the sheets interleaved is 70 then hardened by the application of a cold liquid thereto, and the result is that the sudden change of temperature, instead of being effective at the edges or rims only of the blades, is made to occur with sufficient quick- 75 ness to become effective over the entire area of the blades through the medium of the interleaved sheets, through which the heat of the blades passes away much more rapidly than it could have done through the blades 80 themselves. This result is facilitated in case the edges of the sheets project slightly beyond the edges of the blades, because the 85 projecting edges of the sheets in this case tend to keep the water or other liquid from circulating in direct and immediate contact with the edges of the blades and also expose a greater surface of the interleaved sheets to the action of the liquid, so that the loss of heat occurs at a practically uniform rate 90 throughout the entire extent of each blade.

I have found that in the manner above described I can harden a large number of blades at once without causing them to lose their original flatness to any extent sufficient to 95 interfere with their proper use.

In hardening the blades in stacks as above described the stack of blades and interleaved sheets should be subjected to a powerful chilling action, as by the use of a current or stream 95 of water or of a bath of ice-water or of cold brine. After having been hardened the blades are drawn to a cutting-edge temper, preferably by means of an oil-bath at the proper temperature.

In the accompanying drawings I have illustrated an apparatus useful in practicing my method, in which—

Figure 1 is a front elevation of the hardening apparatus with a portion thereof broken 105 away. Fig. 2 is a central vertical section

through the greater portion of the same viewed at right angles with respect to the position shown in Fig. 1. Fig. 3 is a detail transverse section taken on the line $x-x$ in Fig. 2. Fig. 4 is a side elevation of a holder containing two stacks of blades, together with a frame to which the holder is temporarily secured, as hereinafter described. Fig. 5 is a section on the line $y-y$ in Fig. 4. Figs. 6 and 7 are detail views illustrating a blade and copper sheets. Fig. 8 is a detail view illustrating a latch, hereinafter described. Fig. 9 is a top plan view, and Fig. 10 is a side elevation, of the holder for the stacks of blades and coppers above referred to. Fig. 11 is a plan view of a locking-wedge, hereinafter described.

In the accompanying drawings, 2 and 3 represent two tanks located one above another, means being preferably provided for pumping water from the lower tank to the upper tank, such as pipes 4 and 5, leading through a pump 6. From the lower portion of the upper tank 2 leads a large pipe 7, provided with a valve 8, this pipe and the tank above it being shown as supported by a strong bracket 9, which may be bolted to the wall of a room and to which said pipe 7 is clamped. The lower tank 3 is assumed to stand directly upon the floor, and within the tank is located a supporting-bracket 10, carrying a pair of laterally-extending hollow heads 11. These heads may be cast in one piece, and the channels 12, provided by their hollow interiors, diverge from a central chamber 13, into which leads the lower end of the pipe 7, opposite the inner ends of the channels 12, which thus form outlets for any water which may descend through the pipe 7 from the upper tank 2. Guiding-rods 14 and 15 extend vertically upward from the support 10 to an arm 16, forming a part of the bracket 9, and on these guide-rods is mounted to slide a frame 17, which is represented as rectangular, thus providing a central open portion 18. This frame is connected with a weight 19 through the medium of a cord 20, passing over a pulley 21, by which weight said frame is slightly overbalanced when empty. The valve 8 is provided with suitable operating means, such as a lever 22, pivoted at the top of the tank 2 and connected at one end with the valve by a rod 23 and also provided at its other end with a depending rod 24, on which a collar 25 is rigidly clamped. This collar carries one or more weights 26, the effect of which is sufficient to lift and open the valve 8 when such movement is permitted. For holding the valve closed I have shown a spring-latch 27, adapted to engage a notch 28, cut in the guided lower portion of the rod 24 when the valve 8 is closed. By releasing this latch the weights 26 will be allowed to fall and open the valve 8, and to close the valve the rod 24 is lifted

by hand into the position shown in the drawings. 29 represents a holder adapted to receive a stack of blades, with or without sheets of copper or other quick conducting metal interleaved between them. This holder itself is preferably made of copper and is shown as consisting of a rectangular rim inclosing two open spaces separated by a transverse partition 30. The holder 29 is adapted to be detachably secured in the opening 18 of the frame 17, its lower end being retained therein by lugs 31 and its upper end being retained by spring-actuated latches 32. (Best shown in Fig. 5.) 33 represents a thin sheet-metal blade, such as is shown and described in the Letters Patent above referred to, and 34 represents sheets of copper or other metal having a high degree of heat conductivity.

In practicing my method with the apparatus above described the open spaces of the holder 29 are each filled with a stack comprising a number of untempered blades 33 or similar articles interleaved, respectively, between copper plates, such as 34. At intervals in this stack I prefer to locate steel plates 35, having considerably greater thickness than the blades, in order to prevent any possibility of all the blades being curved in the same direction by the clamping action, hereinafter described, or otherwise. The blades above referred to are usually provided with three perforations, (shown in Fig. 7,) and in this case the coppers 34 and the plates 35 are also provided with perforations adapted to register with the end perforations in the blades, and the entire stack is held in place in the holder 29 by means of steel pins 36 passed endwise through holes drilled in the end portions of said holder, through the perforations in the coppers, blades, and plates, and into holes drilled through the central transverse partition 30 of the holder, as best shown in Fig. 4. It will be understood that these pins remain in place during the hardening operation and are driven out endwise when it is desired to remove the stacks. After the holder has been filled with blades and coöperating parts, as above described, the stacks are compressed, as by means of screw-bolts 37, adapted to pass through threaded perforations formed in the end portions of the holder and to bear against the plates 35, which are preferably made to form the end plates of the corresponding stacks, and while the stacks are under compression wedges 38, Fig. 11, are driven into the spaces opened by the action of the screw-bolts 37 between the end plates 35 and the end portions of the holder, whereupon the screw-bolts 37 are removed. The discharge-openings formed by the outer ends of the channels 12 are given such dimensions that they correspond substantially in length with the exposed edges of the stacks in the holder 29, and the down-

ward movement of the frame 17 is so limited that when in its lowermost position the edges of the stacks will be directly opposite said discharge-openings, respectively. These openings are of such width as will deliver a sufficient volume of water, a width of half an inch being sufficient for the blades above referred to. The holder 29 having been filled with blades, coppers, and plates 35, as above described, the entire holder and its contents are thoroughly heated, preferably out of contact with air or in a reducing atmosphere, to a suitable temperature to produce the desired degree of hardness. This may be done by burying the holder and contents in a quantity of carbonaceous material contained in a muffle and then heating the muffle. Assuming the tank 2 to be filled with water, the heated holder is then immediately placed in the frame 17, as shown in Fig. 5, whereupon the combined weight of the frame and the holder and its contents will overbalance the counterweight 19 and cause said frame and holder to descend into the lowermost position of the frame, thus bringing the edges of the hot stacks opposite the discharge-openings, respectively. The latch 27 is then immediately released, thus causing the valve 8 to open, whereupon the water in the tank 2 rushes down through the pipe 7 and out through the channels 12, from which it is forcibly projected directly against the contents of the holder 29. By the action of this stream of water the heat of the blades is abstracted from them with sufficient rapidity and uniformity to produce a chilling effect equal to that resulting from the plunging of an individual hot blade into cold water, the heat being abstracted through the quick conducting interleaved coppers 34. Inasmuch as copper contracts more than steel for a given drop in temperature, the stacks in the copper-holder 29 will be somewhat compressed by the cooling of said holder, thus preventing any water from getting between the coppers and the blades and avoiding any possible oxidation of the latter. After the water contained in the tank 2 has been discharged through the channels 12, as above described, the frame 17 is raised to the position shown in Fig. 2, the holder 29 is removed therefrom, the screw-bolts 37 are turned in sufficiently to enable the wedges 38 to be withdrawn, the pins 36 are driven out of the stacks, and the blades and coppers are then removed and separated.

The razor-blades above referred to are about one and three-fourths inches long and seven-eighths of an inch wide and have a thickness of about five or six one-thousandths of an inch, and in this case it has been my

practice to use for the hardening process copper sheets having a thickness of about one thirty-second of an inch and made enough larger than the blades to overlap the latter on each edge about one-eighth to three-sixteenths of an inch. For thicker blades or other articles thicker copper sheets should be used.

While the apparatus above described is a convenient and practical apparatus for use in practicing my method, yet my invention is evidently not limited to the use of this or any other specific apparatus.

My apparatus herein described is not claimed herein, being claimed in another application filed by me on the 26th day of May, 1904, Serial No. 209,967.

I claim as my invention—

1. The herein-described method of hardening thin steel articles which consists in interleaving said articles with sheets of metal of relatively high heat conductivity as compared with steel, confining said articles and sheets in a stack, heating said stack, and subjecting the hot stack to the action of a chilling medium, substantially as described.

2. The herein-described method of hardening thin steel articles, which consists in interleaving said articles with sheets of metal of relatively high heat conductivity, confining said articles and sheets in a stack with the edges of said sheets projecting beyond the edges of said articles, heating said stack, and subjecting the hot stack to the action of a chilling medium.

3. The herein-described method of hardening thin steel articles, which consists in interleaving said articles with sheets of metal of relatively high heat conductivity as compared with steel, confining said articles and sheets in a stack, heating said stack and subjecting the hot stack to the action of a flow of cold liquid.

4. The herein-described method of hardening thin steel articles, which consists in interleaving said articles with sheets of metal of relatively high heat conductivity, confining said articles and sheets in a stack with the edges of said sheets projecting beyond the edges of said articles, heating said stack, and subjecting the hot stack to the action of a flow of cold liquid.

In testimony whereof I have hereunto subscribed my name this 22d day of September, 1903.

WILLIAM E. NICKERSON.
